UNITED STATES PATENT OFFICE

CHARLES B. WILLIAMS, OF SHAKER HEIGHTS, OHIO

DESIGN FOR A CLOTHES WRINGER FRAME

Application filed March 27, 1931. Serial No. 39,264. Term of patent 14 years.

To whom it may concern:

Be it known that I, CHARLES B. WILLIAMS, a citizen of the village of Shaker Heights, county of Cuyahoga and State of Ohio, have invented a new, original, and ornamental

Design for a Clothes Wringer Frame, of which the following is a specification, reference being made to the accompanying drawings, forming a part thereof.

In the drawings, Fig. 1 is a front elevation of a clothes wringer frame showing my new design; Fig. 2 is a rear elevation; and Fig. 3 is an end elevation of the end of the clothes wringer frame on which the handle is attached.

I claim:

The ornamental design for a clothes wringer frame substantially as shown.

CHARLES B. WILLIAMS.
